CLAIM

The ornamental design for an electronic lock input dial, as shown and described.

DESCRIPTION

FIG. 1 is a top front perspective view of an electronic lock input dial showing my new design;

FIG. 2 is a bottom front perspective view thereof;

FIG. 3 is a top plan view thereof;

FIG. 4 is a bottom view thereof;

FIG. 5 is a front elevational view thereof;

FIG. 6 is a rear elevational view thereof;

FIG. 7 is a right side elevational view thereof; and,

FIG. 8 is a left side elevational view thereof.

The broken lines indicate unclaimed portions and form no part of the claimed design.
